UNITED STATES PATENT OFFICE

108,811

DESIGN FOR A BRACKET

Alonzo V. Snyder, Los Angeles, Calif.

Application January 10, 1938, Serial No. 74,188

Term of patent 14 years

To all whom it may concern:

Be it known that I, Alonzo V. Snyder, a citizen of the United States, residing in Los Angeles, in the county of Los Angeles and State of California, have invented a new, original, and ornamental Design for a Bracket, of which the following is a specification, reference being had to the accompanying drawing, forming part thereof.

Figure 1 is a perspective view of a bracket showing my new design.

Figure 2 is a side elevational view thereof.

Figures 3, 4 and 5 are sections taken on the lines 3—3, 4—4 and 5—5 respectively of Figure 2.

I claim:

The ornamental design for a bracket substantially as shown.

ALONZO V. SNYDER.
